The ornamental design for the lumbago preventive belt, as shown and described.

DESCRIPTION

FIG. 1 is a front elevational view of a lumbago preventive belt showing the design;

FIG. 2 is a top plan view thereof;

FIG. 3 is a rear elevational view thereof;

FIG. 4 is a bottom view thereof;

FIG. 5 is an enlarged view of a portion thereof between line 5—5 and line 5—5 of FIG. 1;

FIG. 6 is a left side view thereof;

FIG. 7 is a right side view thereof; and,

FIG. 8 is a front elevational view thereof, in use condition. The broken line showing of the person is for illustrative purposes only and forms no part of the claimed design.
